UNITED STATES PATENT OFFICE.

JAMES B. CALKINS, OF PACIFIC, MISSOURI.

LOCKING-NUT.

SPECIFICATION forming part of Letters Patent No. 234,239, dated November 9, 1880.

Application filed April 12, 1880. (Model.)

To all whom it may concern

Be it known that I, JAMES B. CALKINS, of Pacific, Franklin county, State of Missouri, have invented a new and useful Improvement 5 in Locking-Nuts, of which the following is a specification.

This invention consists in making a slight groove or notch at one or more points on the edge of the flat surface of the nut through 10 which the screw passes, and when the nut is screwed down and the surfaces are brought together the nut is locked or prevented from turning by raising a small piece of the opposing surface filling up the notch or notches in 15 the nut. This can be done with a common punch or ordinary diamond-pointed chisel, which is in every-day use.

When the said piece is raised, filling the notch in the nut, it cannot be accidentally 20 knocked off, as it would be if raised on the outside of the nut without the notch to protect it. The chisel forces the piece into the notch like a wedge, firm and solid, leaving an even surface on the outside, the same as before the piece 25 was raised.

I do not claim an instrument for raising the metal on the outside of the nut, as shown in M. H. Dooly's patent, December 5, 1876.

I attain these objects in the manner illustrated in the accompanying drawings, in 30 which—

Figure 1 represents a common nut now in use, presenting notches A A A A cut on its edge; and Fig. 2, notches B B, filled by raising a piece of the adjoining surface, which prevents the nut from turning. 35

Having thus fully described my said invention, what I claim is—

The improvement in locking-nuts, which consists in providing the nut with notches in 40 the edges of its bottom surface, as shown in Fig. 1, and raising the metal of the opposing surface into said notches, as and for the purpose set forth.

JAMES B. CALKINS.
